UNITED STATES PATENT OFFICE.

CLIFFORD C. BROOKS AND EDWIN O. KLEMM, OF FENTON, MICHIGAN, ASSIGNEES TO
KLEMM MANUFACTURING COMPANY, OF FENTON, MICHIGAN.

GRAPHOPHONE STOP MECHANISM.

Original application filed March 15, 1918, Serial No. 222,636. Divided and this application filed January 23, 1922, Serial No. 531,252.

To all whom it may concern:

Be it known that we, CLIFFORD C. BROOKS and EDWIN O. KLEMM, citizens of the United States, residing at Fenton, in the county of Genesee and State of Michigan, have invented certain new and useful Improvements in Graphophone Stop Mechanism, of which the following is a specification.

which the following is specifically set forth:

This invention is a division of our pending application for patent, Serial #222,636, filed March 15, 1918, and described as disclosing certain automatic stopping and certain combined automatic stopping and repeating mechanisms for talking machines.

15 The improvements set forth hereinafter, comprise primarily the stopping mechanism features of the machine of our previous application. This invention involves the use of certain tripping mechanism operable with, and preferably by the tone arm and reproducer, said tripping mechanism controlling the operation of a brake which constitutes the stopping device for the turntable of the talking machine.

20

25 A primary object of this invention has been to produce a type of tripping and controlling mechanisms for the stop or brake device, which eliminates the placing of any load upon the tone arm and reproducer incident to the tripping operation, such a load having the tendency of course to retard the movement of the tone arm and reproducer creating extra friction and wear of the reproducing stylus upon the sound 30 grooves of the record. Our present mechanism does not produce any special increase 35 in friction, but the tone arm and the

of friction between the reproducer and the record, and the matter of eliminating wear or strain upon the sound grooves is of special importance in the art, being conducive to the reproduction of sound of the highest purity of tone, in the operation of the talking machine.

45 Somewhat more specifically stated, the tripping mechanism employed by us is utilized for tripping into action certain moving means which are operated by a motor driven part of the machine, and said part performs the work of tripping the brake or stop from 50 a position in which it is held released or inactive, to cause the brake to be applied to a suitable part of the machine in such a manner as to stop the rotation of the turn-table for the usual purpose of discontinu-

ing sound reproduction. This invention also 55 involves certain disabling devices for throwing out of action the automatic tripping features for our stopping mechanism enabling the stop or brake to be operated manually 60 in what is the customary operation of manual stops.

In the accompanying drawings:

Figure 1 is a perspective view of automatic stopping and repeating mechanisms constructed according to the invention hereof, the rotating platform or table and record thereon being broken away to show parts located therebeneath and certain portions of the base being broken away also for the same purpose; 70

Figures 2 to 6 are fragmentary plan views showing various positions of the driver, connector, tone arm, elevating and tripping members in the cycle of operation beginning with the machine at rest and ending with the machine in the act of reproduction; 75

Figure 7 is a sectional view taken approximately on the line 7-7 of Figure 5;

Figure 8 is a view of the connections intermediate the locking and detent control device and the operation predetermining device, the former being shown partly in section: 80

Figure 9 is a perspective view of the locking and detent device for the adjustable trip showing clearly the lifting plate and its formation with three inclined planes;

Figure 10 is a detail perspective view of the connector or link.

Throughout the following specification and on the several figures of the drawings, like reference characters refer to similar parts.

In the drawings, A denotes the base on which are mounted the motor, record table, and reproducer arm parts, after the conventional manner. This base may constitute the top of the cabinet or the like, such not being material to the invention. The motor parts are not shown, it sufficing to state that they are of usual form and include the centrifugal governor shown at B in Figures 1 and 8, and are adapted to drive the spindle C which carries the record table D. The tone arm E is connected by a universal joint with the base A, for which purpose a socket 1 is secured to the base and receives the ball or lowermost portion

of the arm E in such a way as to afford free upward and lateral movement of said arm E. The tone arm E and its sound box F with the reproducing stylus of the latter 5 constitute the reproducer means of the talking machine and will be generally referred to as such hereinafter.

Driver and reproducer arm actuator.

- 10 Suitably geared with the motor, not shown, so as to be driven thereby, is the driver 2 in the form of a disk having projections 3 on its upper surface. A connector 4 in the form of a link has a hook 5 at one end adapted to move into the path of the projections 3 and when engaged by a projection to be pulled longitudinally by the driver 2. At its other end the link 4 has a downwardly bent projection 6 engaging 20 in an opening 7 of an actuator G shown best in Figure 9, and possessing actuating functions respecting the link 4, the reproducer E and a trip member 8 carried by said reproducer.
- 25 The actuator G is comprised of a plate 9, see Figure 9, the upper portion of which is bent outwardly to provide an actuating cam 10 and a detent flange 11 between which parts is formed a notch 12. Owing to the 30 provision of the notch 12 the actuator G in its relation to the trip 8 forms a locking member for the trip under certain conditions as will appear hereinafter. The plate 9 is rigidly secured to a shaft 13 so as to 35 rock with the latter and the shaft 13 is mounted in suitable bearings in a U-shaped bracket 14 attached to the under side of the base A, see Figure 7. It will be evident that if the connector 4 is engaged at its hook 5 40 with the driver 2 the latter is adapted to pull upon the actuator or locking member G and rock the shaft 13.

The actuator G as seen best in Figures 7 and 9 has secured to it by a bolt 15, a lifting member 16 in the form of a plate which 45 is bent to form three inclined planes or surfaces 16^a, 16^b and 16^c.

Trip device.

- 50 On the pivoted portion of the arm E is mounted the trip member 8 previously mentioned, the same having a friction ring 17 embracing the lower portion of the member E adjacent to the socket member 1. The 55 trip member 8 has a depending vertical lifting arm 8^a, the lower extremity of which is rounded and arranged to engage normally with the inclined plane 16^a of the member 16. By such engagement it becomes evident that a rocking of the shaft 13 and actuator G thereby rocking the plate 16, will 60 result in a rising movement of the plane 16^a aforesaid, thereby correspondingly raising the arm 8^a of the trip member 8. The member 8 being securely fastened to the arm E, 65

preferably by setting of the ring portion 17 in a groove of the member 8, will by the aforesaid action lift the arm E vertically, elevating the stylus thereof from the record. If the movement of the actuator G is 70 only sufficient to cause sliding of the plane or surface 16^a in contact with the arm 8^a until the parts assume the position in Figure 2, the reproducer E will simply be maintained in an elevated position. If the movement is slightly greater so that the lower end of the arm 8^a passes onto the inclined plane 16^b it is evident that the arm will slide down the plane or surface 16^b after the manner shown in Figure 5, resulting in 80 carrying the reproducer outwards by a lateral swinging movement.

It is notable that the trip member 8 is susceptible of rotative movement relative to the reproducer E through the friction connection between the ring 17 and the part E, said ring being virtually a continuation of the member 8. The purpose of this will be set forth hereinafter.

Reproduction point controller.

This controller, designated 18 in Figure 1, is merely an arm formed with a lateral pointer or indicator 19 at its free outer end. At its inner end the controller 18 is curved 95 to extend about two thirds the distance around the socket member 1, as shown at 18^a, and the curved portion is seated in a groove of said socket member. Said curved portion 18^a sufficiently engages the socket member 1 frictionally that the controller 18 will be retained at any fixed adjustment obtained by manipulating said controller freely with the hand. The extremity of the curved portion 18^a terminating at the reproducer E is 100 upturned to form a stop extension 20 and on said extension is adapted to be carried an auxiliary stop 21 in the form of a removable head. A stop member 22 preferably encircled by a rubber buffer piece, projects from the pivoted portion of the reproducer E, is rigid therewith and is adapted to co-act with the parts 20 and 21 under 105 conditions hereinafter stated.

Operation predetermining mechanism.

As seen in Figures 1 and 8, there cooperates with the disk 23 of the governor B a brake shoe 24 carried by a lever 25. A spring 26 tends to pull the end 25^a of the lever 25 toward the toothed edge of a controlling wheel 27. The wheel 27 has regular teeth and notches on its periphery and a special deep notch 28 adapted to be entered by the end 25^a of the lever 25. When 120 the portion 25^a is in the notch 28 the lever 25 will be adjusted so that the shoe 24 may contact with the disk 23 and stop the motor of the machine by preventing rotation of the governor B. It is therefore 125 130

clear that by a simple turning movement of the wheel 27 to disengage the end 25^a of the lever 25 from the notch 28 an adjustment of the lever 25 may be had rendering 5 its brake shoe 24 ineffective and permitting free operation of the governor B, wherefore the motor of the machine may operate to permit the motor to turn the record table D. For adjusting the wheel 27 a 10 spindle 29 is connected therewith and is mounted in a suitable bearing in the base A, said spindle having the knurled knob 30 at its upper end for rotation purposes and the knob having associated therewith 15 a pointer 31, adapted to be moved so as to point to one of various indicia upon a plate 32 attached to the upper surface of the base A. The said indicia preferably comprises the word "Stop", the word "Continuous" 20 and numbers running from 1 to 8 inclusive, but we are not to be limited to this special range of numbering, which corresponds with the number of teeth primarily as provided upon the wheel 27. When 25 the wheel 27 is turned to the left of the position of Figure 8 the notch 28 is opposite the operating projection 34 at the outer end of the actuating bar 35, the opposite end of which bar has a depending arm 36 in 30 the path of an upwardly extending arm 37 on the shaft 13. The bar 35 is spring retracted, by a spring 38, and its projection 34 is adapted to engage the teeth of and turn the wheel 27 excepting only when the 35 notch 28 is opposite said projection. The bar 35 is of course actuated each time a rocking movement is imparted to the shaft 13 and its function is to impart an increment of movement to the wheel 27 as an incident to a reproduction traversing movement of the reproducer E. The bar 35 is 40 incapacitated to perform its function when the notch 28 is opposite the projection 34, this resulting in a continuous operation of 45 the motor and record reproductions by way of repetition operations, as will be more clearly apparent on reference to the foregoing description of a complete cycle of action of our mechanism for stopping and 50 repeating purposes. The bar 35 is mounted to slide in suitable brackets 39 secured to the under side of the base A. Gravitation outward, and the spring 38 acting on the bar 35, tend to rock the actuator G outwards and downwards to engage notch 12 or the outer edge of 11 with the trip part 8^a.

Miscellaneous features.

A keeper 39^a, see Figure 1, is fastened to 60 the upper surface of the base A and extends over the link connector 4 so as to prevent unauthorized lateral shifting of said connector. Associated with the end of the link 4 having the hook 5 is a small knockoff lever 40 and a spring 41 connected to said

lever tends to pull the lever in one direction laterally, the pull being utilized at a predetermined time in the cycle of operation to disengage the hook 5 from the stud or projection 3 with which it may be inter-engaged. Still another spring 42 is attached to the base A near one end of the keeper 39^a and is arranged so that at a certain portion of the movement of the link 4 said spring is pressed against and placed 75 under abnormal tension so that at a later portion of the movement of the link 4 this spring will co-act to carry the link to its inoperative position depicted in dotted lines in Figure 6, at which time the driver 2 80 freely operates and its studs 3 escape the hook 5. In other words, under the conditions stated the hook is out of the path of movement of the studs 3.

The cooperation between the brake shoe 85 24 and the disk 23 of the governor B is somewhat peculiar in that a very quick action brake is obtained. The reason for this is that when the governor B is in operation the centrifugal force of its balls 90 acts to curve the springs supporting them in the customary way. The slightest contact, therefore, of the brake shoe 24 with the disk 23 results in immediate retardation 95 of the turning of the disk whereby the balls approach each other and the straightening force of the springs supporting the balls pushes the disk instantly forwards into the desired positive coaction with the brake shoe 24. 100

As seen in Figure 1, a conventional control device H for the governor B is provided whereby to vary the speed of the motor in playing different selections on the graphophone, this action being well known 105 and not forming any feature of this invention is not described in detail. A pin 49 extends up from the base A intermediate the ends of the link 4 and co-acts with an angular indentation 4^a of said link by having a sort of camming action in respect to the link as seen best in Figure 3. The pin 49 limits the lateral play of the link 4 in 110 one direction.

Complete cycle of operation of the machine.

Figure 2 illustrates the relative arrangement of the trip member 8, lifting device or plate 16 and associated parts when the machine has been stopped through the automatic operation of our invention. It is to be noted that the arrangement depicted is one in which the link 4 is connected with one of the studs 3 of the driver and the lifting plate 16 is held by the link 4 and 125 driver in a position in which said plate is rocked away from the socket member 1. The driver 2 is of course stationary at this time and as a result of the stated adjustment of the plate 16 the lower end of the 130

trip arm 8^a has been caused to ride up the inclined plate 16^b, and has stopped just short of the plane 16^b. Such positioning of the parts has therefore resulted in raising 5 the tone arm or reproducer E vertically and corresponding elevation of the reproducing stylus with respect to the table D and a record which may have been thereon. By being stopped in the uplifted position the 10 reproducer E does not interfere in any way with the ready placing in position on the table D of a fresh record and the removal of a played record.

Starting with the positions of the parts 15 of Figure 2, therefore, as the beginning of a cycle of operation, the first thing required of the operator after placing the record on the table D is the simple grasping of the reproducer E and movement of 20 the latter leftwards as the parts are viewed in Figures 1 and 2. The result of the leftward movement is depicted in Figure 3 which shows the arm 8^a of the trip 8 as having engaged the cam 10 whereby to 25 impart additional rocking movement of the actuator G away from the socket member 1. The said rocking movement of the actuator G imparts longitudinal movement in the same directions to the link 4 until the hook 30 5 is moved sufficiently to enable the knock-off lever 40 to shift the link 4 and disengage the hook from the previously engaged stud 3 as shown in Figure 3. The operator still grasping the reproducer E moves the 35 latter rightwards as soon as the cam actuation previously set forth is effected and the result of the rightward movement is to bring the parts to the positions of Figure 4. In other words, the rightward movement re- 40 lieves the cam 10 of the pressure of the arm 8^a and since the link 4 has been disengaged from the stud 3 the actuator G gravitates toward the socket member 1 effecting interlocking of the arm 8^a in the notch 12. The 45 operator practically as a continuation or part of said rightward movement of the reproducer E deposits the stylus of the latter upon the portion of the record at which he desires the reproduction to stop, or from 50 which he desires repetition of operation to commence. If we assume that a complete reproduction of the record is desired, as is frequently the case, the reproducing stylus will simply be deposited on the innermost 55 groove of the record. It is notable at this point, however, that at whatever position the said reproducer takes relatively to the record, the trip arm 8^a is correspondingly positioned relatively to the notch 12, being 60 interlocked with the notch, such that said arm 8^a will be opposite to and enter the notch when at a later stage of the cycle the reproducer reaches its now predetermined stopping position.

65 The next action for the operator is to

grasp the indicator 18 and move the same so that the pointer 19 thereof assumes a position above the portion of the record at which the reproduction is desired to commence. Usually such portion is at the beginning of the record, its outermost groove, but the adjustability of the member 18 permits of selecting any commencement point desired.

The final action on the part of the operator is to actuate the operation predetermining device, by merely turning the knob or knurled handle 30 to set the pointer 31 properly in relation to the indicating plate 32. If the pointer is moved opposite to the indication "3" the machine will stand adjusted for three reproductions of the record. The moment the handle 30 is turned in the manner stated the wheel 27 is correspondingly turned to disengage the brake shoe 24 from the disk 23 of the governor B and the parts begin to operate according to the movements depicted in Figure 5. That is to say, when the adjustment of the parts of Figure 4 was made the reproducer was in operative contact with the record and since the handle 30 was set the brake being released the driver 2 starts to operate and one of its studs 3 engages the hook 5 of the link 4 thereby pulling upon the link and rocking the actuator or locking member G towards the driver. The rocking causes the lower end of the trip arm A to slide onto the inclined plane 16^b. The weight of the reproducer E causes sliding of the lower end of the arm 8^a down the inclined plane 16^b, thereby bringing the reproducer to the position of reproduction commencement relatively to the record. The reproducing stylus is deposited upon the record at the proper point because the stop member 22 on the pivoted portion of the reproducer engages the head 21 as seen in Figure 5, such engagement constituting the means limiting the extent of outward movement of the reproducer in reaching its reproduction commencement point. The reproduction is of course now commenced and the parts are in substantially the positions represented in Figure 6. That is to say, the arm 8^a of the trip 8 is now in light contact with the detent flange 11 of the actuator G holding said actuator in a position in which it is slightly rocked toward the driver. Of course the turning of the driver relieves the pull on the link 4 and the spring 42 at a proper time shifts the link 4 slightly to the left to the position in dotted lines of Figure 6, enabling the driver studs 3 to rotate without engaging the hook 5. It may be noted that when the link 4 was pulled upon at the time of the action depicted in Figure 5, a rocking of the shaft 13 was produced causing the arm 37 of said shaft to engage the adjacent portion 36 of the bar 35, imparting longitudinal movement to said bar and causing the projection 130

34 of the latter to engage one of the teeth of the wheel 27. An increment of movement is thus imparted to said wheel to turn the same to bring the pointer 31 from a position opposite the indicating numeral "3" of the plate 32 to a position opposite the indicating numeral "2".

The reproducer, according to the position shown in Figure 6, moves steadily toward the center of the record and owing to the frictional connection of the trip 8 therewith moves the trip correspondingly. When the reproducing stylus reaches the point of discontinuance of reproduction the arm 8^a of the trip 8 will be opposite to and enter the notch 12 of the actuator or locking member G. The moment the entrance is effected the parts take the position of Figure 4, bringing the hook 5 of the link 4 again in the path of the studs 3, whereupon the driver 2 is again effective to cause repeat action of the reproducer. This repeat action is merely incident to the parts going through the operations depicted in Figures 5 and 6 again, causing the pointer 31 to move from a point opposite the numeral "2" of the plate 32 to a point opposite the numeral "1". The cycle described then again proceeds and after the second reproduction a third follows after the same manner.

On the completion of the third reproduction the arm 8^a enters the notch 12, as shown in Figure 4, and the link 4 pulls upon the actuator or locking member G to bring the parts to the position shown in Figure 2. Said pull and rocking movement of the actuator G causes the pointer 31 to move with the wheel 27 until the pointer is opposite the indicia "Stop" on the plate 32. Just as the pointer reaches such position the lower end of the arm has reached the position of Figure 2 traveling up the inclined plane 16^c, and the end 25^a of the brake lever 25 has entered the notch 28 of the wheel 27, causing stoppage of the motor and the driver 2. The parts have therefore performed three complete cycles of operation as predetermined by the operation controlling device and the machine is stopped ready for removal of the record and the placing in position of a new record. As thus stopped the reproducer is of course uplifted.

Of course when the handle 30 is turned opposite the indicia "Continuous" on the plate 32 the notch 28 is opposite the projection 34 of the bar 35 and therefore the wheel 27 is not susceptible of being actuated by the bar 35 to bring the wheel to stopping or braking position. Under these conditions the cycles of operation of the reproducer will continue indefinitely so long as the motor works, for reasons previously pointed out.

Of course when the parts have assumed the positions of Figure 2, the arm 8^a is disengaged from the notch 12 so that the trip

8 and reproducer would move together should the reproducer be shifted as is unlikely. The purpose in giving to the reproducer the initial leftward movement as has been heretofore set forth is to enable the trip 8 to be interlocked with the actuator G and held stationary during the time the operator manipulates the reproducer to set the same to the reproduction discontinuance point. An additional purpose of said action is to effect the release of the actuator G so that it will drop, so to speak, toward the socket member 1, lowering the lifting plane 16^a sufficiently to permit the stylus of the sound box F to contact with the record. Whether he moves it in opposite directions in obtaining a nicety of adjustment does not make any difference for the arm 8^a remains stationary, insuring that it will always be in the notch 12 when the required stopping adjustment of the part E is effected.

The plane 16^c might be dispensed with but has an advantage in that should the effect be desired the reproducer when initially moved to the left may be released from the hand and the lower end of the arm 8^a will rest upon the plane 16^c as seen in Figure 3. The inclination of the plane is such that the reproducer will not accidentally swing laterally (as it might do if left as shown in Figure 2). When moving the graphophone from place to place the foregoing adjustment of Figure 3 is useful, and renders in no way unhandy the preliminary leftward shifting of the reproducer to cause co-action of the arm 8^a and cam 10.

The whole cycle of operation summarized, therefore, consists in preliminarily grasping the reproducer and carrying the same leftwards to disconnect the link 4 from the driver and a continuous but reverse movement of the reproducer to interlock the trip arm 8^a in the notch 12, and still additional but continuous movement of the reproducer to deposit its stylus upon the proper point on the record. Next the controller 18 is set, and finally the knob 30 turned to start the machine. Where the record is of the same size as the previous one played and the commencement point of reproduction is unchanged, the manipulation of the controller 18 is not required.

While we have described the operation of our machine in order to obtain one original and two repeated reproductions of the record on the machine, it is obvious that the repeat mechanism may never be used. In other words, the adjustment of the pointer 31 of the predetermining device to bring it opposite the indication "1" by turning the knob 30, will cause the reproducer to make one reproduction of the record and stop automatically in an upraised position, the stop mechanism or brake being of course

actuated by the motor driven part consisting of the driver 2, and the load of operating said brake being in no way placed upon the tone arm and reproducer so as to create undue friction between the stylus of the reproducer and the record. If desired on starting the machine by releasing the brake from the governor disk, the operator may pick up the tone arm and carry it to the starting point on the record by hand. Under some conditions the automatic stopping operation described above may be eliminated and the predetermining device used as a mere manipulator to apply and release the brake as will now be described.

Rendering the automatic stop mechanism ineffective.

Figure 1 of the drawings depicts at 44 a plate secured to the base A and having thereon the indicia "Repeater off". Said plate is slotted and its slot coincides with one formed in the base A. A handle member 45 operates through the plate 44 and base and is connected to a lever 46 beneath the base. The inner end of the lever 46 is pivoted at 47 and its outer end is movable to a point behind the arm 37 of the shaft 13. When so moved it will be obvious that the actuator G is prevented from rocking movement toward the socket member 1 to carry the link 4 from the dotted line position of Figure 6 wherein it is inactive, to the position of Figure 4 required for automatic operation of the stopping mechanism. Under these conditions the automatic operating means for the stopping mechanism will be rendered inactive by the adjustment of the lever 46. On the other hand, the handle 30 of the operation controlling device may be freely manipulated to turn the wheel 27 to and from positions in which the end 25^a of the lever 25 enters the notch 28. The use of the handle 30, therefore, solely for brake control purposes substantially like the use of corresponding manual means on ordinary known types of graphophones, is enabled and the automatic stopping means is inactive.

50 The flange 11 being formed with a contacting edge inclined toward the notch 12 tends to facilitate rather than oppose movement of the tone arm, as the trip 8 approaches the notch 12.

55 This invention is an improvement on that disclosed in our patent No. 1,406,607, dated Feb. 14, 1922.

Having thus described our invention, what we claim as new and desire to secure 60 by Letters Patent, is:

1. In talking machine mechanism of the class described, the combination of a turntable, a reproducing device associated therewith, a motor driven part, a brake for stopping the turntable, means for operating the

brake from the motor driven part, and means controlled from the reproducing device for setting said operating means into action.

2. In talking machine mechanism of the class described, the combination of a turntable, a reproducing device associated therewith, a motor driven part, means whereby to connect the brake with said motor driven part to cause application of the brake for stopping the turntable, a trip movable with the reproducing device, and a part operable at a certain point in the movement of the trip to set the operating means between the motor driven part and the brake into action to enable the brake to be applied by said motor driven part.

3. Means substantially as claimed in claim 2, wherein the trip is adjustable relatively to the reproducing device, the said part being adapted to interlock with the trip for holding the trip stationary under certain conditions, when said trip becomes effective to act upon said part for the purpose stated.

4. In talking machine mechanism of the class described, the combination of a turntable, a reproducing device associated therewith, a motor driven part, relatively movable trip and detent members, one carried frictionally by the reproducing device and movable therewith under certain conditions but adapted to remain stationary under other conditions, the other member engaging the first member for holding it from movement under certain conditions of movement of the reproducing device, and an operating device between the motor driven part and the brake to cause the motor driven part to apply the brake, said operating device being prevented from such action by one engagement between the trip and detent members and permitted to cause said brake applying action by a different engagement between said members.

5. In talking machine mechanism, a reproducing device comprising a tone arm, a turntable, a pivoted plate adjacent the tone arm, a trip frictionally attached to and turning with the tone arm and having a portion engaging with said pivoted plate, said pivoted plate being provided with a notch for receiving the trip, a motor driven part, a connector for connecting the motor driven part with said pivoted plate, the trip being movable in engagement with the pivoted plate so as to hold the latter in a position in which the connector is inactive, but the trip being adapted to enter the notch of the pivoted plate to render the connector active whereby movement of the motor driven part may be communicated to the connector, and a brake adapted to be operated by said connector from the motor driven part.

6. In talking machine mechanism, a tone arm, brake operating means comprising a

pair of normally disconnected members, one of which is pivoted to turn transversely of the other, and one of which is shiftably connected with the tone arm, and means for 5 operating the brake and controlling this engagement of said members.

7. In talking machine mechanism, a turntable, a brake therefor, and a tone arm associated with the turntable, combined with 10 means for releasably holding the brake in non-braking position, means for operating the holding means to release the brake and including a pair of relatively engageable members, one of which is shiftably attached 15 to the tone arm, and instrumentalities adapted to be set into operation by movement of the brake for disengaging the members of the pair from engagement with one another.

8. In talking machine mechanism, a tone 20 arm, a member having a normally fixed but shiftable connection with said arm, a brake for discontinuing operation of the graphophone motor, means releasably holding said brake in non-braking position, a second 25 member riding normally on the first named member but having means of engagement therewith for holding same stationary while the tone arm is manually turned to stop position, and means carried by the second member 30 for releasing the brake from the holding means.

9. In automatic stop mechanism for graphophones, sound reproducing means adapted to move over a record, stop control 35 means normally moving with said sound reproducing means, but adapted to be shifted with respect thereto, movable means controlled by said control means for moving a member into the path of a motor actuated 40 element, motor stop means, means for releasably holding same inoperative, said member being adapted to actuate said holding means to release the stop means when actuated in turn from the motor actuated 45 element.

10. In automatic stop mechanism for graphophones, movable sound reproducing means adapted to be propelled from a sound record groove, a member normally moving 50 therewith and having a frictional adjustment with respect thereto, a second movable member normally held from movement by bearing lightly against the first member, one of said members being provided with 55 a cut-out portion adapted to be entered by the other of said members, whereby the second member is relieved from its bearing against the first member and permitted to move, motor stop means, and motor actuated 60 means for operating said motor stop means brought into operation by said movement of the second movable member.

11. In automatic stop mechanism for graphophones, movable sound reproducing 65 means, a trip thereon and having a fric-

tional adjustment in respect thereto, a plate normally riding lightly on said trip and having a cut-out portion adapted to be entered by said trip when said trip comes opposite same in the movement of said sound 70 reproducing means, motor stop means, means connected with said plate for operating said motor stop means, and motor actuated means for operating the last named means brought into operation by the movement of 75 said plate.

12. In automatic stop mechanism for graphophones, a turntable, movable sound reproducing means, a trip mounted thereon and having frictional adjustment in respect 80 thereto, a plate pivoted on the machine base and adapted to be lightly engaged at one end by said trip, and having a cut-out portion adapted to be entered by said trip, whereby when said trip comes opposite said 85 cut-out portion the plate turns on its pivot, a motor driven projection adjacent to the turntable, motor stop means, and means for operating said motor stop means adapted to be brought into the path of said projection by movement of the said pivoted plate.

13. In talking machine mechanism, the combination of a turntable, a brake therefor, reproducing means, automatic control 95 means intermediate the reproducing means, and means for causing application of the brake to stop the machine, a handle for operating the brake manually, and means for disabling the automatic means for the brake. 100

14. Means substantially as claimed in claim 12, combined with a manual device for operating the stop means, and means for discontinuing the coaction of the projection and the means that works in its path so 105 that the automatic operation of the stop means may be rendered ineffective at will.

15. Means substantially as claimed in claim 10, wherein the last named means may be rendered ineffective to operate the motor 110 stop means, at will.

16. In automatic stop mechanism for graphophones, sound reproducing means, a stop for the graphophone, stop control means movable therewith, a movable plate 115 normally adapted to co-act with said stop control means for effecting automatic operation of the stop, and a manipulatable part having means to co-act with said plate and support it so as to interfere with its cooperation with the said stop control means, whereby automatic operation of the stop mechanism is dispensed with when desired. 120

17. In talking machine mechanism, a tone arm, a member having a normally fixed but 125 shiftable connection with said arm, a brake for discontinuing operation of the graphophone motor, means releasably holding said brake in non-braking position, a second member riding normally on the first named 130

member but having means of engagement therewith for holding same stationary while the tone arm is manually turned to stop position, the portion of the first member 5 on which the second member rides being inclined to facilitate the reproducing progress of the tone arm, and means carried by

the second member for releasing the brake from the holding means.

In testimony whereof we affix our signatures.

CLIFFORD C. BROOKS.
EDWIN O. KLEMM.
